GEORGE DE LAVAL, OF CAMBRIDGE, AND GEORGE P. ABORN, OF BOSTON, MASSACHUSETTS, ASSIGNORS TO THE GEO. F. BLAKE MFG. CO., OF NEW YORK, N. Y., A CORPORATION OF NEW JERSEY.

AIR-COMPRESSOR.

SPECIFICATION forming part of Letters Patent No. 731,692, dated June 23, 1903.

Application filed July 25, 1901. Serial No. 69,638. (No model.)

To all whom it may concern:

Be it known that we, GEORGE DE LAVAL, residing in Cambridge, Middlesex county, and 5 GEORGE P. ABORN, residing in Boston, Suffolk county, Massachusetts, citizens of the United States, have invented certain new and useful Improvements in Air-Compressors, of which the following is a specification.

Our invention relates to air-compressors; 10 and it has for its object to lessen the amount of air compressed and furnished to the receiver should the pressure in the receiver reach above normal. We may accomplish this by holding the inlet-valves of the 15 compressor beyond the usual time of their closing and only partially closing the inlet-valves.

We will describe an air-compressor embodying our invention and then point out the novel features thereof in the claims.

20 In the accompanying drawings, Figure 1 is a view in side elevation of an air-compressor having our invention applied thereto and an engine operating the compressor. Fig. 2 is a detail side elevational view of an air-compressor embodying our invention. Fig. 3 is 25 an end elevation of Fig. 2. Fig. 4 is a detail sectional view of a portion of an air-compressor and showing an inlet and outlet valve. Fig. 5 is a detail view of a mechanism 30 applied to an inlet-valve. Fig. 6 is an elevation, on a larger scale, of a mechanism for controlling the supply of steam to the engine.

Similar letters of reference designate 35 corresponding parts in all the figures.

A represents the cylinder of the compressor, and B a valve for controlling an inlet-opening through which air is drawn into the cylinder. An inlet-opening and valve are provided for 40 each end of the cylinder.

C represents a valve controlling the outlet for compressed air to a receiver or reservoir. (Not shown.)

c represents a conduit through which compressed air is conducted to the receiver from 45 the compressor.

It will be understood that a valve or valves C are provided for each end of the cylinder.

Each inlet-valve B is provided with a stem 50 or shaft b, on which is keyed a latch-disk b'.

Each disk b' is provided, preferably on its periphery, with a shoulder, notch, or projection b², with which a latch or finger b³ is adapted to engage. Each latch or finger b³ is carried by a lever b⁴, which is loosely fulcrumed on the shaft b, and the levers b⁴ are moved on their fulcrums by means of a pitman D, rock-arm D', and rod D², operated by an eccentric d. A spring b⁵ is provided for each finger or latch b³ to hold the finger or 60 latch in engagement with the periphery of the disk b'. Normally when the pitman D is moved the inlet-valve B at one end of the cylinder is being opened, while the inlet-valve at the other end of the cylinder is being 65 closed.

b⁶ represents a lever arm loosely mounted on each stem b. Each lever-arm b⁶ is provided with a projection or extension b⁷, which engages with a lug or other device b⁸, provided on each disk b'. The lever-arms b⁶ are rocked by means of a three-arm lever E, constituting a wrist-plate, fulcrumed on a sliding block F, a rod or link b⁹ being provided between each lever-arm b⁶ and an arm of the 75 lever E. The lever E is operated from the eccentric d through rod E', connected to rock-arm D', so that it moves, together with its connected lever b⁹, reversely to the levers b⁴.

The operation of the mechanism so far as 80 described is as follows, only one valve being considered, as the operation of both valves is the same, the only difference being that when one inlet-valve is being opened the other inlet-valve is being closed. The several parts 85 will have to be so arranged relatively that this can be accomplished. As the eccentric d operates the pitman D in one direction a lever b⁴ is moved on its fulcrum to bring the finger or latch b³ into position to engage the 90 notch b² on the disk, and in the pitman's movement in the reverse direction the lever and latch cause the disk to move, and thus open the valve. The disk b' when moved to open the valve brings the lug b⁸ into position 95 to be operated upon by the lever-arm b⁹. The lever E is so timed to rock on its fulcrum that when the levers b⁴ move the disks to open the valves the lever-arms b⁶ are moving away from the position they occupy after 100

they have moved the disks to close the inlet-valves. Therefore when the levers b^4 have opened the valves the eccentric, through the lever E, is ready to move the lever-arms b^9 into engagement with the lugs b^8 to move the disks and close the inlet-valves. When the lever-arms b^9 move the disks to close the valves, a cam or other device b^{10} engages with a hook b^{11} , connected with the latch b^3 , causing the latch b^3 to hold them out of the way of the disks when the disks are being moved by the lever-arms b^9 . This is the operation of the compressor when the pressure in the receiver is normal. Should the pressure in the receiver go above normal, it is necessary in preventing waste of power, compressed air, &c., to stop the complete compression of all air in the cylinder or to slow down the engine to have a slower compression, and thus save steam and power. To prevent compression of all the air, it is only necessary to delay the closing of the inlet-valves or to prevent their entire closing. To do this in this instance, it is only necessary to shift or change the position of the fulcrum of the lever E so that the throw of its arms will not cause the lever-arms b^9 to move the disks b' at the usual time. This is done by lowering the fulcrum of the lever E, which causes the lever-arms b^9 to move farther away from the point at which they will engage with the lugs b^6 , thereby actuating said disks b' later in the piston-stroke. Therefore with the lever-arms b^9 out of their usual position when the levers b^4 move the disks to a position to have the inlet-valves delayed in closing or to be only partially closed their latches b^3 will merely ride on the peripheries of the disks b' without in any way affecting the disks. The position of the fulcrum of the lever E is in this instance controlled by the pressure in the receiver. A pipe or conduit connects the receiver with a cylinder F', in which a piston f' moves. The rod f^2 of the piston is connected with the sliding block F, on which the lever E is fulcrumed. Guides f^4 are provided for the block F. The piston is moved against the action of a spring f^5 , which is set to resist normal pressure in the receiver. Any pressure above normal will move the piston to lower the fulcrum of the lever. The pressure of the spring is regulated by means of the screw-plug f^6 , through which the piston f' moves. If desired, however, the position of the fulcrum may be controlled by water-pressure, in which case a mechanism such as is described in our co-pending application, Serial No. 69,639.

In addition to the above-described means for regulating the time of closing of the intake-valves the pressure in the receiver above normal may also be employed to cut off the amount of steam supplied to the engine G, which operates the compressor. The engine G is here shown as consisting of a Corliss steam-cylinder, the trips of which are shown in a conventional manner. These trips are regulated by means of a three-arm lever g,

fulcrumed on a stationary bracket g' , and connections g^2 , (conventionally shown by dotted lines). The lever g is rocked by an arm g^3 , which arm is operated from a piston movable within a cylinder g^5 . Rods g^6 g^7 and a rocking lever g^8 serve to connect the piston with the arm g^3 . The piston is provided with adjustable weights to withstand different pressures. The arm g^3 is also connected by a link g^9 with a lever g^{10} , fulcrumed on the bracket g' and carrying a weight g^{11} at one end and having a rod movable in and out of a dash-pot at its other end. Intermediate of its ends it has a connection with the sliding collar g^{12} of the weights of governor, which are rotated in the ordinary manner of Corliss-engine governors.

For the regulation of steam-supply to a plain slide-valve steam end the mechanism above described would operate a balanced throttle-valve.

It is obvious that the above devices or mechanisms are applicable to a single cylinder, two-stage compressing-cylinder, and three-stage compressing-cylinder or more.

What we claim as our invention, and desire to secure by Letters Patent, is—

1. In an air-compressor, the combination of inlet-valves each having a stem, a disk fixed on each stem and having a plurality of notches or projections, levers upon said stems provided with means for temporarily engaging the notches or projections and operated from the eccentric of the engine to move each disk in one direction, and a device operated from said eccentric and controlled by the varying pressure of the air compressed, and connected for positively and variably moving the disks in an opposite direction, in accordance with the variations of air-pressure, to close said valves.

2. In an air-compressor the combination of inlet-valves, each having a stem, a disk fixed to each stem, a lever-arm adapted to engage and move each disk in one direction, which lever-arms are operated from the eccentric of the engine, a lever-arm adapted to engage and move each disk in the opposite direction, a fulcrumed device for operating said last-mentioned levers, and means for shifting the position of said fulcrumed device whereby its throw in closing the valves will be changed.

3. In an air-compressor, the combination with the inlet-valves, each of which has a stem, of a disk for each valve fixed on each stem, an arm operated from the eccentric of the compressor's engine for engaging and moving each disk in one direction, a second arm for each disk, which when engaging and operated moves its disk in the opposite direction, a lever having a movable fulcrumed device for operating said last-mentioned arms, said lever being rocked on its fulcrum from said eccentric, and means operated by excess pressure from the air-receiver for shifting the position of the fulcrum of said lever bodily, whereby its throw is lessened.

4. In an air-compressor, the combination with the inlet-valves thereof, each of which has a stem, a disk provided on each stem, means operated from the eccentric for moving said disk to open the inlet-valves, means comprising a lever having a shiftable fulcrum for moving the disk to close the inlet-valves, and a device operated by excess pressure in the reservoir or receiver for shifting the position of the fulcrum of said lever bodily whereby its effective throw in closing the valves is varied.
5. In an air-compressor, having a cylinder, piston and inlet and outlet valves, the com-

bination of mechanism comprising a movable 15 wrist-plate to actuate the inlet-valves and means open to excess pressure in the receiver or reservoir for changing the position of the wrist-plate whereby closing of the inlet-valves is delayed beyond the usual time. 20

In testimony whereof we have signed our names to this specification in the presence of two subscribing witnesses.
